TAMPERPROOF MAILBOX

Charles B. Browning, Vallejo, Calif.

Application June 27, 1947, Serial No. 757,393

1 Claim. (Cl. 232—22)

1

The present invention relates to improvements in a tamper-proof mail box. It consists of the combinations, constructions and arrangement of parts hereinafter described and claimed.

An object of my invention is to provide a mail box that is adapted to be mounted on a door of a house, or the like, and which is designed in such a manner that access may be had to the mail therein only when the door is opened. Thus, only a person having a key to the door, or who may open the door from the inside of the house, can gain access to the mail.

In conventional building construction, a door is usually hinged to a jamb with the latter projecting forwardly beyond the door when the door is closed. I mount my mail box on the outer face of the door adjacent to the jamb. The latching means for the mail box and the projecting jamb coact with one another to prevent the mail box from being opened as long as the door remains closed. However, upon opening the door, the latching means may be retracted and thus permit the mail to be removed.

A further object of my invention is to provide a tamper-proof mail box that is simple in construction, durable and efficient for the purpose intended.

Other objects and advantages will appear as the specification continues, and the novel features of my invention will be set forth in the claim hereunto appended.

For a better understanding of the invention, reference should be had to the accompanying drawing, forming part of this application, in which:

Figure 1 is a front elevation of my mail box illustrating it as being mounted on the outer face of a door adjacent to the jamb;

Figure 2 is a vertical sectional view taken along the line II—II of Figure 1;

Figure 3 is a horizontal sectional view taken along the line III—III of Figure 1, the door being closed; and

Figure 4 is a view similar to Figure 3, but disclosing the door opened and showing the mail box in top plan view.

While I have shown only the preferred form of my invention, it should be understood that various changes, or modifications, may be made within the scope of the annexed claims without departing from the spirit thereof.

Referring to the drawings in detail, I show a door A that is mounted on a jamb B by means of hinges 1 in the conventional manner. The jamb projects forwardly beyond the outer door face 2

when the door is closed, as in Figure 3. My mail box is designated generally at C. It will be noted that the box is mounted on the outer surface 2 of the door adjacent to the jamb.

The mail box C includes a receptacle having a rear wall 3, side walls 4 and a front wall 5. In Figure 2, I show the rear wall as having a turned back lip 3a, which is abutted against the outer surface of the door. Screws 6 secure this lip to the door, while a lower set of screws 7 anchor the bottom part of the rear wall 3 to the door. The screws 7 cannot be removed as long as the mail box remains closed. The lip 3a is anchored to the door before the rear wall 3 is folded back completely upon the lip.

The top of the box is provided with a mail receiving slot 8, which allows mail to be inserted into the box. The bottom of the box has a mail-discharge opening 9 (see Figure 2). A plate 10 is hinged to the lower end of the rear wall 3, as at 11. When this plate is disposed in the full line position as shown in Figure 2, the discharge opening 9 is closed. Upon swinging the plate 10 toward or beyond the dot-dash line position in Figure 2, the mail is discharged from the box.

A keeper 12 is anchored to the plate 10 by rivets 14, or other suitable fastening means. This keeper has a rolled over end defining a pin-receiving eyelet 12a. A pin guide 15 is secured to the front wall 5 by a rivet 16, or other means. This guide has a pair of pin-receiving eyelets 15a (see Figure 1) that are arranged to register with and straddle the eyelet 12a of the keeper when the plate 10 is closed.

In order to retain the plate 10 in closed position, I provide a pin 17 that is moveable endwise through the registering eyelets 12a and 15a, thus latching the plate against being opened. A spring 18 encircles the pin 17 and yieldingly urges the latch through the registering eyelets, as shown in Figures 1 and 3. This spring encircles the pin and is disposed between the right-hand wall 4 in Figure 1 and a small bar 18a extending transversely through the pin 17. The pin 17 extends through an opening 19 formed in one of the side walls 4, and has an operating knob 20 on the projecting end of the pin positioned exteriorly of the receptacle or mail box for manual manipulation.

Referring to the Figures 1 and 3, it will be noted that the jamb B is disposed to prevent the pin 17 from being retracted from the keeper 12 when the door A is closed. Thus the plate 10 cannot be opened while the door remains closed. However, when the door A is opened, as in Figure 4, the

knob 20 will clear the jamb and the pin 17 may be retracted from the keeper. At this time the plate 10 may be opened to permit discharge from the box. The knob 20 is spaced slightly from the jamb to prevent marring of the latter.

After the mail has been discharged, the plate 10 may be closed again and the pin 17 moved endwise through the registering eyelets 12a and 15a by the spring 18. Upon closing the door A, the jamb B will prevent the pin from being retracted until the door is opened again.

In Figure 1, the door A has its right-hand edge hinged to the jamb B. When the left-hand door edge is hinged to a jamb on the opposite side of the door opening, the pin is removed from the opening 19 and is reassembled so that it will not project toward the left through an opening 19a formed in the left side wall 4 of the mail box (see Figure 3.)

I claim:

A mail box designed to be positioned on either a right-hand or a left-hand opening door and adjacent to a jamb on the hinged side of the door; the mail box comprising a receptacle having a mail-receiving slot at its top and a mail-discharge opening at its bottom; a plate hinged to the receptacle for closing the mail-discharge opening; a keeper anchored to the plate and having a pin-receiving eyelet; a pin guide secured to the receptacle and having a pair of eyelets arranged to register with and straddle the eyelet of the keeper when the plate is closed; a pin slideable in the eyelets of the guide and extending

through one side of the receptacle; the pin being moveable endwise for passing through the eyelets of the guide and keeper when the eyelets are in registration, and thus locking the plate against being opened; the other side of the box having an opening in registration with the eyelets of the guide and adapted to slidably receive the pin, whereby the pin may be placed on either side of the box so as to be adjacent to the jamb when the door is closed and thus be prevented from being withdrawn until the door is opened.
